(57) **CLAIM**

We claim the ornamental design for an apparatus support bracket, as shown and described.

DESCRIPTION

FIG. 1 is a front perspective view of an apparatus support bracket of our new design;

FIG. 2 is a rear perspective view thereof;

FIG. 3 is an elevation view of a first side thereof;

FIG. 4 is an elevation view of a second side thereof opposite said first side;

FIG. 5 is a top plan view thereof;

FIG. 6 is a bottom plan view thereof;

FIG. 7 is an elevation view of a third side thereof; and,

FIG. 8 is an elevation view of a fourth side thereof opposite said third side.

The broken line showing in FIGS. 2, 4, and 6 is included for the purpose of illustrating portions of the apparatus support bracket and forms no part of the claimed design.
